T. A. BIGGS

OIL BURNER

Filed Nov. 3, 1923

FIG. 2

FIG. 1

INVENTOR.

T. A. Biggs.

BY

Milton S. Graudall,
ATTORNEYS.

FIG. 3

UNITED STATES PATENT OFFICE.

THOMAS A. BIGGS, OF SIOUX CITY, IOWA.

OIL BURNER.

Application filed November 3, 1923. Serial No. 672,678.

To all whom it may concern:

Be it known that I, THOMAS A. BIGGS, a citizen of the United States, and a resident of Sioux City, in the county of Woodbury and State of Iowa, have invented certain new and useful Improvements in Oil Burners, of which the following is a specification.

This application is a continuation in part 10 of my application No. 609,731, filed December 29, 1922, which application I have abandoned by a written declaration of abandonment submitted herewith.

My invention contemplates in an oil 15 burner of the general type wherein the fuel is vaporized in a heated, pervious mass of refractory material the production of certain novel improvements, appurtenances and features of construction whereby the fuel is 20 thoroughly atomized and admixed with the proper proportion of oxygen to form a completely combustible gas.

A further object of the invention is the 25 production in an oil burner having an oil vapor emitting enclosure of an improved adjustable air flue, which directs a current of air downwardly into the center of the column of vapor, which insures an intimate mixture of the air and vapor and which is 30 readily adjustable toward and from the enclosure.

The invention has for another object the 35 production of an oil burner which emits a hollow column of oil vapor, downwardly into the center of which is directed a current of air which intimately admixes with the surrounding volume of oil vapor, forming a mixture which is completely combustible, and which makes a maximum amount of 40 heat from a minimum quantity of fuel.

The invention further contemplates an oil 45 burner having an air flue which directs the current of air downwardly toward a column of oil vapor, and which is so constructed that the current of air admixed with the oil vapor may be readily shifted laterally with respect to the column of oil vapor to neutralize the tendency of other air currents or drafts to interfere with the intimate and 50 uniform admixing of the air and oil vapor, which uniform mixture must be had to produce a flame of uniform intensity and regularity.

Still further the invention has for an object 55 the production of an improved burner of this general type which is simple and

comparatively inexpensive in manufacture and installation, yet is durable and efficient and produces a maximum amount of heat from a minimum quantity of fuel.

These and other objects and advantages I 60 successfully attain in the embodiment hereinafter described, defined in the appended claims and illustrated in the accompanying drawing which forms a part of this application and in which like characters of reference indicate corresponding parts through the several views, of which,—

Fig. 1 is an elevation of a burner constructed in accordance with my invention, parts being cut away and shown in section.

Fig. 2 is a horizontal section of the same taken on the offset line 2—2 of Fig. 1, and

Fig. 3 is a plan of the modified form of 75 the air flue head.

The burner illustrated is particularly designed to be installed within a stove or furnace, and comprises an enclosure or container which may be a conical bowl, 4, having a vertical upper rim, 5. In installing the device, the bowl, 4, is preferably supported by a sheet metal plate, 6, placed upon the grates or other support of the furnace, stove or other heater (not shown). The center of the bottom of the bowl, 4, is provided with a depending nipple, 7, which projects below the plate, 6, and on which is threaded a T-pipe fitting, 8, the lateral and lower openings of which are considerably reduced, and into the lateral thereof is 80 threaded an oil feed pipe, 9, which, it will be understood, communicates with a suitable source of oil supply. The lower end of the T, 8, may be further reduced by a bushing, 10, into which is threaded an oil 85 overflow pipe, 11, and into the upper end of the bushing, 10, is threaded the upper end portion, 12, of the overflow pipe, said pipe, 12, being extended through yet spaced from the nipple, 7, and on the exterior of 90 the pipe, 12. In the bottom of the bowl, 4, is inserted a screen, 13, and the bowl, 4, is then filled to substantially the lower edge of the rim, 5, with a mass of gravel, ashes, earth, steel wool, asbestos or other suitable 95 refractory material, 14, adapted to provide a mass through which the oil from the pipe, 9, permeates and which, when heated, will 100 vaporize the oil. I have found from my many experiments, however, that washed 105 gravel or gravel clear from sand affords the best results. Obviously, the overflow pipe,

12, should extend to or slightly above the surface of the mass, 14. The breadth of the burner flame is limited by a flat ring, 15, which is removably supported above and 5 preferably rests upon the mass, 14, said ring being preferably provided on its inner periphery with a flange, 16. In manufacture of the device these flat rings are provided in various sizes whereby the capacity of the 10 burner may be altered without altering the size of the bowl, 4.

It will now be clear that the oil is fed upwardly through the mass of material, 14, it being heated by the heat from the burner, 15 as it passes therethrough and as the oil permeates the extremely hot surface of the mass it is thoroughly vaporized and rises in a column of vapor from the bowl and when properly admixed with air, as previously described, provides a blue and white uniform flame above and a distance from the bowl.

I provide an air flue consisting of a vertical section, 17, which projects downwardly 25 through the plate, 6, and is rotatably supported at one side of the bowl as by segmental arms, 18, formed integrally with the rim, 5, of the bowl, partially encircling the flue section, 17, and supporting a suitable 30 boss, 19, on the flue. Above the flue section, 17, is a return bend flue section, 20, one end portion of which telescopes and is supported by the upper end portion of the section, 17. The eduction end, 21, of the section, 20, is positioned a distance above and directed downwardly in axial alignment 35 with the bowl. The other end portion of the section, 20, is formed with a helical end edge, 22, which rests upon a lateral projection, 23, on the section, 17, whereby the section, 20, is supported and the mouth of the section, 21, may be adjusted toward or from the bowl by holding the section, 20, against rotation and rotating the section, 17, in the 40 appropriate direction.

In order to thoroughly vaporize the fuel and at the same time facilitate the intimate admixing of the air and oil vapor rising from the bowl, I have found it desirable to 50 so restrict the column of vapor that it rises only from the perimeter of the bowl. For this purpose I place in the upper portion of the mass, 14, an imperforate plate, as a sheet metal disk, 24, having a central opening 55 to admit the overflow pipe, 12. The said disk, 24, is spaced from the walls of the bowl, 4, and is preferably embedded in the mass, 14, just below the surface thereof. By virtue of this construction it will be 60 clear that the oil seeping upwardly through the mass, 14, will be converted into gas which is emitted upwardly from the bowl and around the disk, 24, in what may be called a hollow column, as will be understood from the upwardly-directed arrows. 65

It will be understood, however, that although the disk, 24, increases the efficiency of the burner and reduces somewhat the consumption of fuel, its presence is arbitrary.

The device is so constructed and designed, 70 and its parts so related that the draft from the draft or smoke pipe of the usual heater will draw a continual current of air upwardly into the flue, 17, which current of air is directed downwardly a distance from 75 the mouth of the flue section, 21, and into the center of the hollow column of the oil vapor rising from the bowl and intimately mixed with the surrounding volume of gas. Obviously, the distance of the eduction end 80 of the flue section, 21, from the top of the bowl is of great importance, but when properly constructed and installed, the burner makes a blue and white flame and the combustion takes place a distance above the 85 bowl.

The air from the draft flue tends to cool the central portion of the surface of the mass, 14, or that portion thereof above the plate, 24. The embedded plate, 24, is of 90 copper, or other good heat-conducting material, and therefore, through capillary attraction, is always hot, and the oil coming in contact with the bottom thereof is converted into gas which is emitted at the sides 95 of the plate. In other words, the disk, 24, serves not only to cause the vapor to rise in a hollow column, but also to provide in the central portion of the mass, 14, a generating element which is not cooled by the air 100 current.

There are occasionally heater installations which do not have the proper draft for oil burners, although suitable for solid fuel. Therefore, in such instances I provide means 105 for slightly forcing and assisting the draft toward the usual draft or smoke flue, which consists of an electric fan, 25, which forces air into a suitable duct, 26, communicating with the lower end of, yet which does not 110 interfere with free rotation of, the flue section, 17. Under the ordinary and usual conditions, however, it is not necessary to use the elements, 25 and 26.

As previously stated, the eduction end of 115 the air flue is normally aligned coaxially with the bowl, 4, whereby with normal draft conditions the current of air from the flue uniformly admixes with the surrounding volume of gas and thus produces a uniform flame around the burner. There are occasions, however, where an air current within the heater or the draft from its smoke pipe tends to so divert either the rising volume of gas or the air current from the flue, or both, as 120 to result in unevenness of combustion. That is, the flame would be greater at one side of the burner than the other. This evil tendency in some instances may be successfully neutralized by swinging the flue sec- 125 130

tion, 20, slightly in one direction or the other. In order to prevent this evil under all conditions of draft, I provide means, readily adjustable, to direct the air current eccentrically to the column of gas and in the proper phase to produce a uniform mixture of the air and gas, and thereby cause uniform combustion around the burner. The said means preferably comprises a head 5 plate, 27, on the exhalation end of the flue section, 20, having an eccentric opening, 28, the said plate being rotatably supported on the flue section by means of projecting lateral studs, 29, on the flue section which project 10 into a channel rim, 30, on the plate. The top of the channel is provided with radial notches, 31, which, when brought into registration with the studs, 29, permit mounting and demounting of the plate upon and form 15 the flue.

When the burner is installed in heaters which do not have shifting air currents, the flue may be provided with a removable head, as presented in Fig. 3, which may be identical in every respect with that above described 20 with the exception that it has a concentric opening, 32. In manufacture these heads are provided with the opening, 32, thereof of various sizes to restrict the air current to 25 the proper volume.

Although I have illustrated and herein-after described the preferred embodiment of my invention, I would not be understood as being limited to such specific construction, 30 for various alterations may be made in the details of construction and arrangements of parts herein disclosed without departing from the spirit and scope of the invention as defined in the following claims, to-wit,—

40 1. An oil burner embodying a container, a pervious mass of refractory material therein, an oil feeding passage communicating with the bottom of the container, an oil overflow pipe projecting through said passage 45 and extending substantially to the top of said mass, and a plate adjacent the top of the mass, and spaced from the container walls.

2. An oil burner embodying an open top 50 container, a pervious mass of refractory material therein, an oil feeding passage communicating with the bottom of the container, and an imperforate plate adjacent the top of the mass and spaced from the walls of the

55 tainer opening.

3. An oil burner embodying an open container, a pervious mass of refractory material therein, means for feeding oil upwardly through the mass, an imperforate plate embedded in the mass and spaced from the walls of the container, and a ring removably supported on the mass to limit the capacity 60 of the burner.

4. An oil burner embodying a container, an air flue having an end directed downwardly toward the container, and a removable head on the flue having an opening eccentric to the opening of the air flue.

5. In an oil burner, a container, and an air flue including a rotatable vertical section at the side of the container, a return-bend section having one end portion telescoping 70 the vertical section and formed with a helical end, the other end being directed toward the enclosure, and a projection on the vertical section engaging the helical end of the other section, whereby rotation of the vertical section raises and lowers the return-bend 75 section.

6. In an oil burner, an open top container, a pervious mass of refractory material therein, means for feeding oil upwardly therethrough, an imperforate plate adjacent the top of the mass and spaced from the container walls, and a flue above the container having an end directed downwardly toward 80 the container.

7. In an oil burner, a container, and an air flue including a rotatable vertical section at the side of the container, a return-bend section having one end portion telescoping 85 the vertical section and the other end directed toward the enclosure, the telescoping end of one of said sections being helical, and a projection on the telescoping end portion of the other section engaging said helical end, whereby rotation of the vertical section raises and lowers the return-bend section.

8. An oil burner embodying a container, an air flue having an end directed downwardly toward the container and a rotatable head on the flue having an opening eccentric to the opening of the air flue.

In testimony whereof, I have hereunto set 105 my hand this 26 day of October, 1923.

THOMAS A. BIGGS
